UNITED STATES PATENT OFFICE.

SAMUEL GLENVILLE BROSUS, OF SAVANNAH, GEORGIA.

BOILER.

SPECIFICATION forming part of Letters Patent No. 511,115, dated December 19, 1893.

Application filed May 8, 1893. Serial No. 473,329. (No model.)

To all whom it may concern:

Be it known that I, SAMUEL GLENVILLE BROSUS, of the city of Savannah, county of Chatham, State of Georgia, have invented certain new and useful Improvements in Boilers, of which the following is a full, clear, and exact description, which will enable others skilled in the art to which it appertains to use the same.

10 An object of my invention is to produce a boiler in which provision is made for returning the products of combustion through one or more return flues whereby the full effect of the heat of the burning gases from such 15 combustion is passed to the water, and producing a great economy in the utilization of the heat, which, in boilers of the usual construction, is allowed to escape, and to produce a boiler which will be especially adapted to 20 the locomotives. This and other objects are accomplished by constructions hereinafter shown and described.

My invention consists in certain novel features of construction and arrangement hereinafter described and particularly pointed out 25 in the claims.

In the drawings—Figure 1 represents an end view of the flue boiler with one half of the water head removed. Fig. 2 is a cross section of the boiler taken on the line xy , xy , Fig. 1, and showing the flues and return flue boxes in section. Figs. 3, 4, 5 and 6 are respectively, end elevations and sections of the return flue boxes, the respective sections being taken on the lines $x'y'$ and $x''y''$. Fig. 7 is an end elevation showing flue box for connection of two flues.

Like letters of reference refer to like parts throughout the several views.

40 The boiler B is provided with fire flues, F' , F'' , F''' . Flues F' receive the products of combustion directly from the furnace, through the return flue box, R' , to flue, F'' , thence through return flue box, R , to flue, F''' , and so 45 carry the said products to and fro through the said boiler while being burned and before they escape to the stack or chimney, by which means the heat of the products of combustion is brought several times in contact 50 with the water surrounding the tubes, and

thereby causing said products of combustion to give up their full heat to the surrounding water.

To the two boiler heads or flue sheets, A and D, the return flue boxes are secured by 55 bolts b , passing through the holes b' in the flange R^2 of said box, to their respective boiler heads, by which means the said flue boxes are securely bolted or riveted to said heads. The said flue boxes are designated as separated 60 return flue boxes, and are arranged to connect the flues in independent series or corresponding rows by which the products of combustion are passed through separate successive series of flues, so that there may be a 65 more equal distribution of the products of combustion through all the flues. The flanges are provided with the holes b' which may be countersunk to receive the holes of the bolts b whereby the same are protected from the 70 heat. T represents the walls of said flue boxes. These boxes when secured in place, as shown in Figs. 1 and 2 connect a series of flues together, so as to cause the products of combustion to make a circuitous route through 75 the boiler. In the construction shown in these figures, I have connected one series of flues with another series, but, as is obvious, one flue in one row could be connected with a corresponding flue in the upper row by the box 80 shown in Fig. 7, or the flue box R, may be divided by partitions R^3 , indicated in dotted lines Fig. 4, by which means two corresponding flues can be connected together.

H represents a groove or recess cut in the 85 compact surface of the boxes R, so that any suitable packing as fire clay or lead, may be used to pack the said boxes tight against the boiler heads A and B. These flue boxes are each provided with caps f which when removed, afford ready access for cleaning tools 90 to clean out the flues of the boiler, to permit access thereto for any desired purpose.

At one end of the boiler, as shown in the Fig. 2, there is provided a water head E' , 95 which may be formed by the continuation of the boiler shell and the supplemental head E. Openings are provided in the head D which induces a circulation of the water between said head and the main boiler; the said water 100

head in addition to causing a circulation also protects the return flue boxes R from burning out by surrounding said flue boxes with water. These boxes R may be made of any desirable material, such as iron, copper, steel or fire clay, but when under pressure, as shown between heads D and E, Fig. 2, should be made of suitable metal to stand the pressure in the boiler.

- 10 The arrows S', S², and S³, indicate the course of the products of combustion through the boiler, and S⁴ the outlet; but the order may be reversed so that F³, receives and F' discharges. The flues F³ are secured to the supplemental head E and said head is caught or secured tightly around the return flue boxes R. If desired an additional water box could be arranged in front of head A in a similar manner to that at the left hand.
- 15 The water in the jacket of the flue boxes R' may be in free communication with the boiler, or if desired the feed water may be heated on its way to the boiler by passing through said jacket.
- 20 The flue boxes R, or R' may be used as found advisable, either in combination, or singly and on one or both heads, with or without the water head E'. The flue boxes R' are provided with water jackets E² which is
- 25 formed by the outer wall T', and the inner wall T, thus providing a circulation chamber through which water is passed, being forced through the inlet J and discharged at outlet J'.
- 30 I do not limit myself to the arrangements and constructions shown, as the same may be varied without departing from the spirit of my invention.

Having thus ascertained the nature and set forth the construction of my invention, what I claim as new, and desire to secure by Letters Patent, is—

1. In a steam boiler, the combination with the flue sheets and flues thereof, of a return flue box having a cap which permits access thereto, and a flange between the walls of said box by which the said box is secured in place, substantially as set forth.
2. In a steam boiler, the combination with the flue sheets and flues thereof, of a return flue box having a cap which permits access thereto, a flange between the walls of said box by which the said box is secured in place and a water head surrounding said return flue box and thereby protecting the same, substantially as set forth.
3. In a steam boiler, the combination with the flues and flue sheets, of separated return flue boxes adapted to connect the corresponding ends of the flues in independent series, whereby the products of combustion are passed through separate successive series of flues; said flue boxes being also provided with

caps which permit access to said boxes and flues, substantially as set forth.

4. In a steam boiler, the combination with the flues and flue sheets, of separated return flue boxes adapted to connect the corresponding ends of the flues in independent series whereby the products of combustion are passed through separate successive series of flues, substantially as set forth.

5. In a steam boiler, the combination with the flues, of return flue boxes adapted to connect the corresponding ends of the flues, and an independent water jacket for each return flue box, substantially as set forth.

6. In a steam boiler, the combination with the flues, of separated return flue boxes adapted to connect the corresponding ends of the flues in independent series, and a flange provided with countersunk holes for the reception of bolts by which each of said boxes is secured in place, substantially as set forth.

7. In a steam boiler, the combination with the flue sheets and flues thereof, of separated return flue boxes adapted to connect the corresponding ends of said flues, in independent series and a water head surrounding said flue boxes and in open communication with the main boiler, substantially as set forth.

8. In a steam boiler, the combination with the flue sheet and flues thereof, of separated return flue boxes adapted to connect the corresponding ends of the flues in independent series, whereby the products of combustion are passed through separate successive series of flues, said flue boxes having a recess to receive suitable packing to make a tight joint with the flue sheet, substantially as set forth.

9. In a steam boiler, the combination with the flues of return flue boxes, provided with a partition or partitions forming separate chambers and connecting the corresponding ends of the flues, substantially as set forth.

10. In a steam boiler, the combination with the flues, of return flue boxes provided with a partition or partitions forming separate chambers and surrounded by water and connecting the corresponding ends of the flues, substantially as set forth.

11. In a steam boiler, the combination with the flues and flue sheets thereof, of return flue boxes attached to the flue sheet and surrounded by water and adapted to connect the corresponding ends of the flues, substantially as set forth.

In testimony whereof I have signed my name to this specification in the presence of two subscribing witnesses.

SAMUEL GLENVILLE BROSIUS.
